(57) **CLAIM**

The ornamental design for a gun cleaning kit bag, as shown and described.

DESCRIPTION

FIG. 1 is a perspective view of a gun cleaning kit bag showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the gun cleaning kit bag where the gun cleaning kit bag is in a configuration of use; and,

FIG. 10 is an enlarged view of portion 10 shown in FIG. 1. The broken lines in the drawings depict portions of the gun cleaning kit bag that form no part of the claimed design.
